UNITED STATES PATENT OFFICE.

JOSEPH RAOUL LA RIVIÈRE, OF WATERWAYS, ALBERTA, CANADA.

SPRING WINDER FOR PHONOGRAPH MOTORS.

Application filed January 16, 1924. Serial No. 688,662.

To all whom it may concern:

Be it known that I, JOSEPH R. LA RIVIÈRE, a subject of the King of Great Britain, residing at Waterways, in the Province of Alberta and Dominion of Canada, have invented new and useful Improvements in Spring Winders for Phonograph Motors, of which the following is a specification.

The object of my said invention is the provision of a peculiar and advantageous device for bringing about the winding of the spring of a motor employed for the rotation of the record table of a phonograph.

To the attainment of the foregoing, the invention consists in the improvement as hereinafter described and definitely claimed.

In the accompanying drawings, forming part of this specification:—

Figure 1 is a view partly in elevation and partly in section, showing a portion of a phonograph and my novel device arranged in proper relation to the spring motor of the phonograph.

Figure 2 is an enlarged diametrical section of my novel device, the same being shown as properly arranged relative to a part of the spring motor.

Figures 3 and 4 are transverse sections taken in the planes indicated by the lines 3—3 and 4—4, respectively, of Figure 2.

Similar numerals of reference designate corresponding parts in all of the views of the drawings.

The phonograph 1 is of the ordinary or any other suitable construction as is also the spring motor 2 for rotating the record table 3, the said spring motor including the usual socket member 4, interiorly threaded as shown in Figure 2 and appropriately supported in the phonograph.

In accordance with my invention the horizontal wall 1^x of the phonograph or phonograph casing is provided at 5 with a vertically disposed aperture, and also in accordance with my invention my novel winding device is disposed under the said horizontal wall 1^x and entirely within the phonograph casing 1 so as not to offer any obstruction from said casing 1.

My novel device per se is best shown in Figures 2, 3 and 4, and by particular reference to said figures it will be observed that a threaded shaft 6 is disposed in the threaded socket member 4 which member 4 is in connection with the spring motor 2 in the ordinary well known manner. The shaft 6 is

carried by a body 7 which is preferably of general cylindrical form, and in the end of the body 7 remote from the shaft 6 is a socket 8 of circular form in cross section which serves to loosely receive the inner end of a shaft 9, said shaft end being also of circular form in cross section. Fixed to the outer end of the body 7 is a ratchet 10, and opposed to the said ratchet 10 is a spring pressed pawl 11, carried by a circumferentially grooved drum 12 which is loosely mounted on the shaft 9. A cable 13 is connected to and adapted to be wound on the drum 12, and is carried through the aperture 5 in the casing wall 1^x and is provided with a finger piece 14 which as shown by full lines in Figure 1 is adapted to bring up against the said wall 1^x and to normally rest thereagainst. Surrounding the shaft 9 and arranged at the outer side thereof in a housing 15 is a convolute spring 16. The housing 15 is fixed with respect to the drum 12, and one end of the spring 16 is connected to the shaft 9 while the other and outer end of the spring 16 is connected to the housing 15. In this connection it will be observed that the housing 15 is opposed to a closure disk 17, loose about the shaft 9, and that the outer end of the said shaft 9 is fixed against rotation in and supported by a bracket 18 pendent from the casing wall 1^x.

At 19 the casing 1 is provided with a cover which may be and preferably is hinged in the ordinary manner.

In the practical use of my novel winding device it will be understood that normally the cable 13 and its finger piece 14 will be arranged as shown by full lines in Figure 1, it being simply necessary when it is desired to wind the spring of the motor 2 for the operator to grasp and pull the finger piece 14 upwardly to the position shown by dotted lines in Figure 1. When the finger piece 14 and cable 13 are pulled upwardly as stated, the drum 12 will be rotated in one direction against the action of the spring 16, and a portion of the cable 13 will be led off of the drum 12, the said rotation of the drum 12 acting through the pawl 11 and the ratchet 10 to rotate the body 7 and through the body 7 the before mentioned member 4 to wind or tension the spring of the motor 2. When the finger piece 14 is released the spring 16 will operate to turn the drum 12 in reverse direction so as to bring about the taking up of the cable 13 on the drum 12 and the res-

10 toration of the finger piece 14 to the position shown by full lines in Figure 1. By repeating the operation described, the spring of the motor 2 may be expeditiously and 5 easily wound or tensioned to the extent desired. It will also be apparent that my improvement obviates the necessity of employing a crank or any other unsightly projection in conjunction with the phonograph.

10 I have entered into a detailed description of the construction and relative arrangement of the parts embraced in the present and preferred embodiment of my invention in order to impart a full, clear and exact understanding of the said embodiment. I do 15 not desire, however, to be understood as confining myself to the specific construction and relative arrangement of parts inasmuch as in the future practice of the invention various changes and modifications may be made 20 such as fall within the scope of my invention as defined in my appended claims.

Having described my invention, what I 25 claim and desire to secure by Letters-Patent, is:—

1. The combination in a phonograph, of 30 a spring motor for rotating a record table, said motor including a rotary member having a threaded socket, a body having a threaded shaft disposed in said member and also having a socket in its opposite end, a casing in 35 which said motor and said body are arranged, a shaft supported in the casing and also supported in said body and held against

rotation, a ratchet fixed with respect to the 35 body and loosely surrounding the shaft, a circumferentially grooved drum loosely surrounding the shaft and carrying a spring 40 pressed pawl arranged to cooperate with said ratchet, a cable connected to and adapted to be wound on said drum and extending through an aperture in a wall of the casing, a finger piece on said cable and adapted to bring up against said wall, a 45 housing fixed to the said drum, a convolute spring in said housing and connected at its inner end to the shaft and at its outer end to the housing, and means loose on the shaft for closing said housing.

2. The combination of a phonograph casing, a shaft mounted therein and held against rotation, a spring motor in the casing and having a rotary member in connection with its spring for the winding or tensioning of the spring, a body rotatable about 55 the shaft and connected with said member, a ratchet fixed to said body, a drum loose on the shaft and having a pawl opposed to said ratchet, a spring surrounding and connected to the shaft and also connected to the drum, 60 and a cable secured to and adapted to be wound on the drum and extending through an aperture in a wall of the casing and having a finger piece adapted to bring up against said wall.

65 In testimony whereof I affix my signature.

JOSEPH RAOUL LA RIVIÈRE.
